UNITED STATES PATENT OFFICE.

AARON H. WOLFF, OF NEW YORK, N. Y.

DESIGN FOR A GAS HEATER.

Application filed May 10, 1922. Serial No. 2,170. Term of patent 14 years.

To all whom it may concern:

Be it known that I, AARON H. WOLFF, a citizen of the United States, residing at the borough of Manhattan, in the city, county, and State of New York, have invented a new, original, and ornamental Design for Gas Heaters, of which the following is a specification, reference being had therein to the accompanying drawing, which forms a part thereof.

The accompanying drawing shows a front view in perspective of a gas heater embodying my design.

As indicated in the drawing, the upper part of the front portion of the heater about the opening for the radiant heating elements is concaved and polished so as to constitute a reflector, and the horizontal part at the bottom of the opening is corrugated.

I claim:

The ornamental design for a gas heater, as shown.

AARON H. WOLFF.
